CLAIM

The ornamental design for a cart, as shown and described.

DESCRIPTION

FIG. 1 is a perspective view of an embodiment of a cart showing a new design;

FIG. 2 is a front view thereof;

FIG. 3 is a rear view thereof;

FIG. 4 is a side view thereof;

FIG. 5 is another side view thereof;

FIG. 6 is a top plan view thereof; and,

FIG. 7 is a bottom plan view thereof.

Texture also forms no part of the claimed design in any of the Figures and may be replaced in the formal drawings with untextured material, without departing from the design disclosed. The inventors anticipate that the invention can be any part, portion, element, or combination of elements of the depicted cart. For example, the wheels shown in the Figures may be shown as environmental.
